UNITED STATES PATENT OFFICE.

FRANK T. GLEESON, OF NATIONAL SOLDIERS HOME, VIRGINIA.

WAXING MACHINE.

Application filed May 17, 1926. Serial No. 109,718.

This invention relates to a device for waxing and cleaning floors and the like, the general object of the invention being to provide a device provided with a holder for a receptacle containing wax or other material which is to be applied to a floor, with means for feeding the material from the holder to that portion of the floor over which the device is passing, with means carried by the device for rubbing the material into the floor.

Another object of the invention is to provide means whereby a cloth can be attached to the device to polish the floors after they have been waxed or otherwise treated.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a perspective view of the device.

Figure 2 is a sectional view.

Figure 3 is a view of the closure for the opening in the device.

Figure 4 is a view of the top plate.

Figure 5 is a view of the grooved plate.

Figure 6 is another view of the grooved plate and showing the bottom plate therein.

Figure 7 is a view of one of the shoe plates.

Figure 8 is a view of the bottom plate.

Figure 9 is a view of a modification.

In these views, 1 indicates the top plate which is provided with a central opening 2 and the bolt holes 3. A collar 4 surrounds the opening and is spaced from the walls thereof and has a perforated ear 5 thereon to which the handle 6 is pivoted. A flanged plate 7 engages the bottom face of the plate 1 and has an opening 8 therein which is considerably smaller than the opening 2 in plate 1. A flanged collar 9 is fastened to the plate 7 and this collar will lie in the opening 2 when the plates are placed together. This collar has the passages 10 therein which communicate with the annular gutter 11 in the plate 7, grooves 11 radiating from the gutter to the ends of the plate. This plate is also provided with the bolt holes 12 which register

with the holes 3 in plate 1. A bottom plate 13 fits in the space formed by the flanges of the plate 7 and has a central opening 14 therein which registers with the opening 8 in plate 7. This plate 13 is also provided with the bolt holes 15 and has a cleat 16 on its bottom face, one on each side of the opening 14. A pair of shoes 17 have their reduced upper portions engaging the plate 13, with their bottom portions engaging the cleats and the end flanges of the plate 7. Each shoe carries a pair of bolts 18 which pass through the bolt holes in the other plates, with their upper ends receiving the wing nuts 19, so that the bolts will hold the different parts assembled. The shoes are to be covered with suitable fabric 20 to form the rubbing surfaces.

A plug or disk 21 closes the bottom of the central space formed by the holes in the plates and permits the material to collect in said space and flow through passages 10 into the gutter and through the grooves 11 to the ends of the device. The collar 4 forms a holder for a container, such as shown at A in Figures 1 and 2, for wax or other material used with the device.

In using the device, the cover of the container is perforated, as at a, and then the container is inverted and placed with its lower end in the collar 4. Thus the wax or other material will pass from the container into the central space and will pass therefrom through the grooves and drop upon the floor at the ends of the device. The fabric covered shoes will then distribute the material upon the floor and will rub it into the floor.

The material dropping from the edges of the perforated cover will drop directly into the gutter and will thus pass through the grooves to the ends of the device. If desired, the plug 21 can be removed so that the material dropping through the opening in the center of the device will fall directly upon the floor, while the portions dropping into the gutter will pass through the grooves to the ends of the device.

Toothed strips 22 may be held on the plate 1 by the wing nuts 19 and their bolts, these strips holding a cloth, such as shown at 23 in Figure 1, in place so that floors can be polished or cleaned. If desired, the plate 1 can be used alone for this purpose and the cloth stretched over it and held in place by the strips 22. If desired, a container holding a cleansing fluid can be placed on the plate 1

so that some of the fluid will drop upon the cloth through the opening 2 and thus enable the device to be used to clean floors. After the floors are thus cleaned, the container and the wet cloth would be removed and a dry cloth placed on the plate 1 to polish the floor. The device could be used in the same manner with all the plates in position and the plug 21 removed so that the cleansing material would drop through the central openings upon the cloth and be acted on by the shoes.

Figure 9 shows a device of but one-half the size of that shown in the other figures, with the parts made single instead of double. In all essential particulars, this device is the same as that before described.

From the foregoing, it will be seen that I have provided a simple device for waxing, polishing and cleaning floors and which will evenly distribute wax or other material upon the floor, the device holding the original container of the wax or other material.

It is thought from the foregoing descrip-

tion that the advantages and novel features of my invention will be readily apparent.

I desire it to be understood that I may make changes in the construction and in the combination and arrangement of the several parts, provided that such changes fall within the scope of the appended claim.

What I claim is:—

A device of the class described comprising a flat body having a centrally arranged opening passing therethrough, a flange on the top of the body around the opening and spaced therefrom to form a seat for a container, a handle connected with the body, a pair of pads carrying shoes engaging the lower face of the body and spaced apart to leave the opening free, bolts connected with the shoes and passing through the body adjacent the ends thereof and nuts on the bolts for detachably connecting the shoes with the body.

In testimony whereof I affix my signature.

FRANK T. GLEESON.
